UNITED STATES PATENT OFFICE.

MAX LEHR, OF BROOKLYN, NEW YORK.

DESIGN FOR A BANNER, FLAG, PENNANT, SIGN, EMBLEM, OR ARTICLE OF A SIMILAR NATURE.

53,507.

Specification for Design.

Patented July 8, 1919.

Application filed May 25, 1918. Serial No. 236,656. Term of patent 7 years.

To all whom it may concern:

Be it known that I, MAX LEHR, a citizen of the United States, and a resident of the city of New York, borough of Brooklyn, in the county of Kings and State of New York, have invented a new, original, and ornamental Design for a Banner, Flag, Pennant, Sign, Emblem, or Article of a Similar Nature, of which the following is a specification, reference being had to the accompanying drawing, forming a part thereof.

The figure is a face view of the banner showing my new design.

I claim:

The ornamental design for a banner, flag, pennant, sign, emblem, or article of a similar nature as shown.

MAX LEHR.
